UNITED STATES PATENT OFFICE.

FRANZ A. BOEDTCHER, OF BERGENFIELD, NEW JERSEY.

SYSTEM FOR CONTROLLING THE OPERATION OF ELEVATORS.

Application filed May 25, 1920. Serial No. 384,117.

To all whom it may concern:

Be it known that I, FRANZ A. BOEDTCHER, a citizen of the United States, residing at Bergenfield, county of Bergen, and State of New Jersey, have invented a certain new and useful System for Controlling the Operation of Elevators, of which the following is a specification.

This invention relates to elevator operating systems, and is, more particularly, directed to the governing of the car controlling circuit, for the purpose of effecting proper and safe operation of the car at all times.

In elevator systems as hereinbefore installed, it has been the practice to control these circuits, in such manner, that the elevator car is precluded from starting from a floor at which it is previously stopped until the shaft door at said floor has been closed. This is for the purpose of protecting persons from walking through shaft doors, which have been left open, after a car has left the floor, and, for the further purpose of precluding the car operator from starting the car while passengers are leaving or entering the same through the floor opening. While these systems have been very useful in the overcoming of accidents of this character, such systems have led to the dangerous practice, on the part of car operators, to throw the controller into a full speed position, while the floor door is open, so that the car will start at full speed, as soon as the door is closed, and the controller circuit completed by the switch normally associated with the floor door. The purpose of this practice is to obtain rapid service, but it will be manifest to those skilled in this art, that the sudden imposing of the full force of electrical energy upon the motor, which operates the car, through the carrying out of this practice, results in such an inrush of current to the armature, that the burning out thereof not infrequently occurs. Moreover, the sudden starting of the car from a dead stop to full speed imposes a tremendous strain upon the operating mechanism of the elevator and the cables which support and carry the same, thus rendering the practice specified very dangerous and at times highly expensive because of repairs, and adjustments necessitated thereby. In fact, elevator cars are

very often overloaded, or at least loaded to their maximum capacity, with the result that the sudden acceleration of the operating mechanism, as described, places an overload on the cables which may cause them to snap with serious loss of life.

With these considerations in mind, one of the objects of the present invention is to provide an elevator controlling system, wherein it is normally, absolutely impossible for a car operator to start the car, except from neutral. That is to say, a system wherein the car can only be started by operating the controller circuit successively through its different speeds, starting at the lowest.

In the elevator controlling systems as heretofore installed, it has further been suggested to provide a controller circuit with a switch, which it was required to close before the controller circuit could become operative to effect movement of the car. This switch was electrically controlled and was included in a circuit also including switches controlled by the opening and closing of the floor doors. The door switch circuit was usually of the open circuit type and the door switches were so constructed, that when any door was open, the switch circuit was closed and served to open the switch which governed the controlling circuit. This construction operated with high efficiency so long as all of the electrical connections and wiring remained intact and were properly insulated. As soon, however, as ground occurred in the door switch circuit or one or more of the fuses, which are normally included in switch circuits, "blew" out, the switch controlling the operating circuit of the elevator frequently became permanently closed so that the car could be operated at will and entirely beyond the control of the door switches with the result that the car could pass up and down the shaft with all of the doors open.

With these considerations in mind, a second object of the present invention is to provide an elevator controlling system, wherein the grounding of any portion of the door switch circuit, or, a breaking of said circuit, due to the blowing of the fuses or the leaving of a floor door in dangerous condition, while the car is at rest at a floor, will preclude the movement of the car and im-

mediately apprise the operator thereof that something is wrong with the door switch circuit. In such instances, however, he has recourse to emergency means, which will enable him to move the car for the purpose of detecting the cause of the failure of the door switch circuit to operate and to allow any passengers who may be in the car to leave the same at an adjacent floor. The object of the emergency means is particularly to overcome any chance of a car being stalled between floors.

The use of emergency means for the purpose of allowing the movement of a car after the controlling circuit has been automatically rendered inoperative, for any one of several reasons, has been heretofore carried out in practice, and the emergency mechanism has been almost universally of the electrically operated type, and has generally been controlled through a push button or other form of switch positioned in the car and normally protected against tampering by inquisitive persons through the housing of said switch within a casing having a glass closure. In the event of trouble, the operator is supposed to break the glass and operate the switch to enable him to move the car independently of the door switch circuit. There is a strong tendency on the part of operators, however, to become careless and it very frequently occurs that, if a door switch circuit cease to operate, the glass closure is broken and the emergency switch thrown on to render the car operative, not only for immediate necessities, but for continued operation. In other words, after the emergency switch has been operated, the car operator finds that he can operate the car satisfactorily and does not bother to lay up the car for repairs of the circuit, but continues to operate the same through long periods of time without the protection of the door switch circuit, whereby the doors of the elevator shaft may be left open or closed at will without in anywise effecting any control of the operations of the elevator car without the safety normally incident to the use of such circuit.

Moreover, a third object of the present invention is to provide emergency means with which it is practically impossible to operate the elevator for any appreciable time after the door switch circuit has become ineffective. In the preferred embodiment of the invention, the door switch circuit is controlled at the respective floors by the floor door locks so that it becomes, in effect, a door lock circuit which can only be operated through the actual locking or unlocking of the door and independently of any movement of the door. Preferably, this circuit is of the open circuit kind, being closed when all of the locks are in locked condition, whereby the unlocking of any particular

lock brings about the breaking of the circuit and renders the same inoperative.

In contradistinction to the electrically controlled emergency means of the prior art, the emergency means of the present invention is entirely mechanical and is furthermore entirely independent of the door switch circuit. It is thus not dependent for its operation on the door switch circuit, as is practically every prior electrical emergency device for electrical elevators, and, accordingly, cannot be rendered inoperative by the failure of the door switch circuit to operate.

A fourth object of the present invention is to so construct an elevator controlling system that the controlling circuit is normally governed by a switch which is adapted to be positively and mechanically closed, but is adapted to be thereafter and while the car is at rest at a floor, maintained closed by a door switch circuit which, of itself, does not possess the ability to close said switch. In other words, the door switch circuit becomes, practically speaking, purely a maintaining circuit and is not a switch operating circuit as has universally been the case in prior constructions. By so constituting this system, an operator is positively precluded from starting an elevator except through successive speeds and cannot start it on "high". For the reason that, if the controller is out of neutral when the door switch circuit is completed, said circuit is incapable of closing the switch of the controller circuit and the car will simply remain at a standstill until the controller is moved to neutral position and then operated in the proper manner.

Features of the invention, other than those specified, will be apparent from the herein-after detailed description, taken in conjunction with the accompanying drawings.

The accompanying drawings illustrate one practical embodiment of the invention, but the construction therein shown is to be understood as illustrative, only, and not as defining the limits of the invention.

The drawings illustrate diagrammatically a system embodying the present invention.

Referring to the drawings, 1 designates a floor or platform of an elevator car which is mounted for vertical travel in an elevator shaft as common, and the car is fitted with a suitable controller 2 having a handle 3 by means of which the controller may be operated for the purpose of controlling the movements of the car. The handle 3 of the controller is mounted on a controller lever 4 which carries movable contacts adapted to be shifted through the operation of the handle into engagement with fixed contacts 5 for the purpose of effecting movement of the car in either an upward or downward direction depending on the direction of rotation of the lever 4 from the neutral position in which it is shown in full lines in the

drawings. The controller construction described forms no part of the present invention and may be of any conventional form, but has been referred to briefly to facilitate a thorough understanding of the present invention. Certain of the fixed contacts 5 of the controller are electrically connected through wires 6 and 7, through suitable electrical means with the motor and correspond, respectively, to the upwardly and downwardly directions of movement of the car, and certain other of the contacts 5 are connected by a common wire 8 to the motor, whereby a circuit through the controller may be completed either through the wires 7 and 8 or through the wires 6 and 8 depending upon the direction in which it is desired to move the car. Included in the common wire 8 is switch mechanism 9, which may be mounted in any suitable position on the car either above the platform and suitably housed or below the platform. By means of this switch mechanism the controller circuit for the motor may be governed so as to render said circuit operative or inoperative.

The switch mechanism, which is designated generally by the reference numeral 9, embodies an insulating supporting plate 10 to which is pivoted a rocker 11 on a pivoted pin 12. The rocker 11 embodies a bridge shaped member 13, preferably of metal having rigid therewith a non-magnetic portion 14 having a foot 15 provided with an aperture 16. The free end of the bridge member 13 is provided with an apertured tail piece 17 and carries a forwardly projecting pin or stud 18. The stud 18 works in the bifurcated end of a movable switch member 19 pivoted on a pin 20 which is, in turn, supported on a bracket 21. The bracket 21 is secured to the plate 10 by means of screws 22, one of which serves as a binding post for one lead of the wire 8. When the rocker is tilted such movement thereof is adapted to cause pivotal movement of the switch member 19 to bring the same into and out of engagement with a fixed contact 23 which is mounted on the plate 10 by means of screws 24 one of which serves as a binding post for the other lead of the wire 8. Thus, through the rocking movement of the rocker 11, the switch embodying the fixed contact 23 and the movable contact 19 may be opened or closed to govern the operativeness of the controlling circuit through the common wire 8.

The rocker 11 may be constructed of metallic and non-metallic material as specified or may be constructed entirely of non-metallic material, so long as an armature 25 which is carried by the portion 14 is insulated from the rocker. The armature 25 is mounted on the rocker 11 for cooperation with a core 26 of a magnet 27 and is preferably coiled around the core 26 as shown. The magnet

and its core are secured to the plate 10 by means of screws 28.

The coils of the magnet 27 are included in a door switch circuit 29, which circuit also includes a plurality of door switches 30, one of which is positioned adjacent the door of each floor of the elevator shaft. The switches are so constituted that they tend to assume an open position either under the influence of a spring 31 or by gravity or in any other suitable manner, but are adapted to be normally held closed at such times as the elevator door is in closed and locked position by means of a portion of the lock of said door. For an illustrative showing, 32 designates the locking latch of the lock pivoted at 33 and adapted to cooperate with the keeper 34. When the latch is in engagement with the keeper, the door is locked in closed position and the weight of the latch rests upon the switch 30 and causes the closing of the switch. However, as soon as the latch is raised to unlock the door, the switch automatically opens and breaks the circuit 29. As soon as the door is again locked, the switch again is closed by the latch. Accordingly, the locking and unlocking of the door controls the door switch circuit and even though a door is closed and the lock fails to operate to lock the door in closed position, the circuit 29 will remain inoperative until the door is locked. The system of this invention, accordingly, does not rely for its operation upon the opening and closing of the door which at times would be very apt to leave the door switch circuit in operative condition, while the doors were left in an unsafe condition, wherein they could be opened by unauthorized or curious persons with the result that accidents could occur.

The door switch circuit 29 is energized from any suitable source and embodies fuses 35 and 36 in its leads. Particular attention is moreover called to the fact that the positive lead of this circuit passes directly to the door switches which are connected in series and that the negative lead passes directly to the coil 27. This is a very important feature from a practical standpoint since any grounding at the switches will immediately render the coil 27 inoperative and probably blow the fuse 35. If the polarity of the leads were reversed, any ground in the lead which passes directly through the coil 27, so long as it occurred at the distant side of the coil as, e. g., in one of the door switches, would leave the coil in an energized condition and would not immediately render it dead as with the polarity illustrated in the drawing. With the coil 27 constantly energized, the car might be run at will whether the doors were locked or unlocked. Accordingly, the parts of the system should be wired as shown, so that

any grounding at the door switches or in any other part of the positive lead will immediately render the coil 27 dead.

Another important feature of the present invention is inherent in the fact that the current in the door switch circuit 29 is so weak that it will not normally attract the armature 25, for the purpose of closing the switch in the wire 8. In practice, the bridge portion 13 is made heavier than the portion 14, so as to normally gravitate into a position to disengage contacts 19 from contacts 23 in the controller lead 8, and simultaneously lift the armature 25 away from the core of the coil 27. Under these conditions, the circuit 29 is of insufficient strength to attract the armature 25 and close the switch in the controller lead. However, if the rocker 11 is tilted to bring the armature into engagement with the core 26, while the door switch circuit 29 is completed and energized, said circuit is of sufficient strength, in the absence of the gap between the armature 25 and its core to hold the rocker in this position and maintain the switch of the controller lead closed. The door switch circuit 29 thus becomes what may be termed a maintaining circuit and is not to be confused with operating circuits, since it has not the power to attract its armature and close the switch, but merely serves to hold the switch closed after said switch has been placed in this condition, through the employment of means associated with the controller. Said maintaining circuit thus has an entirely different function from that which would be the case if it were in the form of an operating circuit adapted, of itself, to close the switch of the controller circuit, and as will be hereinafter more fully explained accomplishes an entirely different result occasioning absolute safety in the operation of the system.

The switch of the controller circuit is adapted to be closed through the tilting of the rocker 11 by means operated by the controller and, as shown, this means consists in a plurality of weights 37 secured to a rod 38 which passes upwardly through the aperture 16 in the foot 15 of the rocker and is provided with a stop 39 as shown. The weights when imposed on the rocker through the rod 38 and stop 39 overbalance said rocker, close the switch in the controller lead 8, and bring the armature 25 into operative relation with the coil 27, and this is the position which the parts occupy when the controller lever 4, to which the rod 38 is connected by a flexible connection 40, is in neutral position as shown with the elevator car at a standstill. The flexible connection runs over a pulley 41 so that when the controller lever is moved from the neutral position shown to a position shown in dotted lines, wherein it is adapted to support the

elevator, the weights are lifted and the stop 39 raised to the dotted line position. If all the elevator door locks 32 are in locked condition, the lead 8 of the controller circuit will be completed at the switch 19, and said circuit will be completed through the lead 7 to effect movement of the car. This is for the reason that the maintaining circuit will be energized and its coil 27 will hold the rocker in a tilted position to close the switch at 19.

However, if at the time of shifting the controller lever, one of the door locks is unlocked, the corresponding switch 30 thereof will be open and as soon as the weights 37 are lifted, the switch in the lead 8 of the controller circuit will be opened and the car cannot start. For the same reason, an operator cannot move the controller lever on to a given speed while a door is open and cause the elevator car to automatically start when the door is closed and locked as is the case in prior systems because this would leave the rocker in a position to break the controller circuit and when the door was locked the maintaining circuit, while completed, would be of insufficient strength to close the switch and start the car. With the present invention, the car must be started by the controller from a neutral position.

There are times in the operation of an elevator when it is desirable to be able to move the same irrespective as to whether the door switch circuit is operative or not, such, e. g., as in case of fire when said circuit may become grounded, in case moisture should ground said circuit, or in the event that some unauthorized person should reach in through the floor door and unlock the same. In any of these instances, the trouble might occur while the elevator car is between floors in which event, the car would, under the safety provisions of this system, immediately stop. For this reason, emergency means is provided which will allow of the further operation of the car to enable the same to be moved to a position to allow of the exit of any passengers who might be aboard, or to permit of the running of the car in case of fire so that the occupants of the building may be rescued.

Emergency mechanism has heretofore been used, but is invariably electric and usually forms part of the door circuit. In either instance, trouble with the door circuit or fire is apt to render the emergency means inoperative thereby greatly endangering the lives of the persons in the car or building. According to the present invention, the emergency mechanism is made entirely independent of the door circuit and is furthermore purely mechanical. It consists in the illustrative form shown of a rod 42 which passes through the aperture 17 of the tail piece on the rocker and has a stop 43 at the

lower end thereof. The upper end of the rod 42 is affixed to one end of a lever 44 pivoted at 45 and provided at its other end with a finger piece 46. The lever 44 is housed 5 within a suitable casing 47 positioned in any convenient place within the car and the finger piece 46 protrudes through one end of the casing. However, the lever is normally precluded from operation by a plate of glass 10 48 which is positioned within the casing and forms a strut or obstruction to the downward movement of the finger piece.

In case of emergency, the operator may break the glass 48 and thereafter push down 15 the finger piece 46 which will rock the rocker in a counterclockwise direction and close the switch of the controller circuit at 19. However, in order to operate the car such operator must hold the finger piece 46 down for 20 as soon as he releases it the parts will gravitate to a position to open the switch. In this manner, the car is rendered operable during emergency but the finger piece 46 cannot be pushed down and left in this position 25 to allow of continued use of the car. This permits of operation of the elevator in case of fire, but is so inconvenient that an operator would not otherwise attempt to run the elevator through the controlling period, 30 as one of his hands must constantly be employed when the elevator is running to hold down the finger piece 46. Accordingly, the heretofore prevalent tendency to simply switch out the floor switch circuit in case 35 anything became wrong therewith and to operate the car indefinitely without the protection of such circuit is overcome by the present invention and the operator is practically forced to operate his car under maximum 40 conditions of safety.

In the invention, as thus far specifically described and shown in the drawings, the controller circuit is of the single wire type, but, there are other well known forms of 45 controller circuit embodying double or triple wiring. It will be understood that the single wire circuit shown in the drawings is for the purpose of illustration, only, and that if the wire 8 is duplicated for double, 50 triple, or more circuits, the switch in said circuit is merely duplicated and all of these switches may be secured together as will be understood by any one skilled in the art, so as to be operated from a single gravity member 55 as described in connection with the single circuit.

Moreover, while the invention has been specifically described as particularly adapted for use in governing the controller circuit 60 of the car, it will be understood that the switch described as in the wire 8 of the controller circuit, might be left out of this circuit, and, instead, included in the operating circuit of the elevator without departing 65 from this invention. In this event, the

controller circuit would be completed, as soon as the controller handle is thrown over, but the operating circuit would be broken unless all the door switches were closed and door locks locked. 70

These changes, as well as others, will result from the association of the invention with elevators of different types and the invention is not to be understood as restricted or limited to the specific structure 75 shown therein. It is to be construed as broadly novel as is commensurate with the appended claims.

Having thus fully described the invention, what I claim as new and desire to secure by 80 Letters Patent is:

1. In a system of the class described, an elevator car provided with a controller, a controller circuit, a switch in said controller circuit, mechanical means associated with the controller and with the switch and mechanically operated by the controller for automatically effecting a closing of the switch when the controller is in neutral and the car at rest, a lock associated with the 85 shaft door of each floor, a switch associated with each lock and operated thereby, and electrical means associated with the door switches and controlled thereby for maintaining the controller circuit switch in 90 closed condition when the car controller is moved from neutral to start the car provided that all the locks are in locked condition to close the door switches. 95

2. In a system of the class described, an 100 elevator car provided with a controller, a controller circuit associated with the controller, a switch in the controller circuit, mechanical means associated with the controller and with the switch and mechanically 105 operated by the controller for effecting the closing of the switch when the controller is in neutral position and the car at rest, a lock associated with the shaft door of each floor of the building in which the elevator is 110 installed, and electrical means controlled by all of said locks for maintaining the controller circuit switch in closed condition, when the controller is shifted from neutral position to start the car, provided that all 115 of the locks are in locked condition. 115

3. In a system of the class described, an elevator car provided with a controller, a controller circuit associated with the controller, a switch in the controller circuit, mechanical means associated with the controller and with the switch and mechanically 120 operated by the controller for effecting the closing of the switch when the controller is in neutral position and the car at rest, a lock 125 associated with the shaft door of each floor of the building in which the elevator is installed, and electrical means controlled by all of said locks for maintaining the controller circuit switch in closed condition, 130

- when the controller is shifted from neutral position to start the car, provided that all of the locks are in locked condition, in combination with manually operable mechanical 5 emergency means for temporarily closing said switch to allow of movement of the car, even though the electrical switch maintaining means is ineffective.
4. In a system of the class described, an 10 elevator car provided with a controller, a circuit associated with the controller, a switch in said circuit, mechanical connections between the controller and the switch for positively and automatically effecting a 15 closing of the switch when the controller is in neutral position and the car at rest, locks associated with the floor doors of the shaft in which the elevator is installed, and electrical means controlled by said locks for 20 maintaining the controller circuit switch in closed condition when the controller is moved out of neutral position to start the car, provided that all of the door locks are in 25 locked condition.
5. In a system of the class described, an 30 elevator car provided with a controller, a circuit associated with the controller, a switch in said circuit, mechanical connections between the controller and the switch for positively and automatically effecting a 35 closing of the switch when the controller is in neutral position and the car at rest, locks associated with the floor doors of the shaft in which the elevator is installed, and electrical means controlled by said locks for 40 maintaining the controller circuit switch in closed condition when the controller is moved out of neutral position to start the car, provided that all of the door locks are 45 in locked condition, in combination with manually operable mechanical emergency means for temporarily closing said switch to allow of movement of the car, even though the electrical switch maintaining means is ineffective.
6. In a system of the class described, an 50 elevator car provided with a controller, a controller circuit associated therewith, a switch in the controller circuit, a gravity member cooperating with the switch and adapted to normally gravitate into a position to open the switch and render the controller ineffective to start the car, mechanical connections between the gravity member and the controller for automatically moving the gravity member into position to close the switch when the car controller is in neutral position, switches on the floors of the building 55 in which the elevator car is installed, and electrical means, operable only when all of said switches are closed and the gravity member in a position to close the controller circuit switch, to hold said gravity member in such position when the car controller is moved from neutral position to start the car.
7. In a system of the class described, an 60 elevator car provided with a controller, a controller circuit associated with the controller, a switch in said circuit, mechanical connections between the switch and the controller for positively and automatically closing the controller circuit switch, a plurality of switches associated with the several floors of the building, and a maintaining circuit 65 operable to maintain the controller circuit switch closed only after it has been closed by the controller and when the switches of all floors are closed.
8. In a system of the class described, an 70 elevator car provided with a controller, a controller circuit associated therewith, a switch in the controller circuit, a gravity member cooperating with the switch and adapted to normally gravitate into a position to open the switch and render the controller ineffective to start the car, mechanical connections between the gravity member and the controller for automatically moving the gravity member into position to close the switch when the car controller is in neutral position and the car at rest, a plurality of switches corresponding to the respective floors of the building in which the elevator is installed, and electrical means controlled by said switches and cooperating with the gravity member to maintain the 75 same in a position to hold the controller circuit switch closed, when the car controller is shifted from neutral to start the car, provided that the switches of all floors are closed.
9. In a system of the class described, an 80 elevator car provided with a controller, a controller circuit associated therewith, a switch in the controller circuit, a gravity member cooperating with the switch and adapted to normally gravitate into a position to open the switch and render the controller ineffective to start the car, mechanical connections between the gravity member and the controller for automatically moving the gravity member into position to close the switch when the car controller is in neutral position and the car at rest, a plurality of switches corresponding to the respective floors of the building in which the elevator is installed, and electrical means controlled by said switches and cooperating with the gravity member to maintain the 85 same in a position to hold the controller circuit switch closed, when the car controller is shifted from neutral to start the car, provided that the switches of all floors are closed.
10. In a system of the class described, an 90 elevator car provided with a controller, a controller circuit associated therewith, a switch in the controller circuit, a gravity member cooperating with the switch and adapted to normally gravitate into a position to open the switch and render the controller ineffective to start the car, mechanical connections between the gravity member and the controller for automatically moving the gravity member into position to close the switch when the car controller is in neutral position and the car at rest, a plurality of switches corresponding to the respective floors of the building in which the elevator is installed, and electrical means controlled by said switches and cooperating with the gravity member to maintain the 95 same in a position to hold the controller circuit switch closed, when the car controller is shifted from neutral to start the car, provided that the switches of all floors are closed.
11. In a system of the class described, an 100 elevator car provided with a controller, a controller circuit associated therewith, a switch in the controller circuit, a gravity member cooperating with the switch and adapted to normally gravitate into a position to open the switch and render the controller ineffective to start the car, mechanical connections between the controller and the gravity member for lifting the gravity member into a position to close the switch when the car controller is in neutral position, switches on the floors of the building in which the elevator car is installed, and electrical means, operable only when all of said switches are closed and the gravity member in a position to close the controller circuit switch, to hold said gravity member in such position when the car controller is moved from neutral position to start the car.
12. In a system of the class described, an 105 elevator car provided with a controller, a controller circuit associated with the controller, a switch in said circuit, mechanical connections between the switch and the controller for positively and automatically closing the controller circuit switch, a plurality of switches associated with the several floors of the building, and a maintaining circuit 110 operable to maintain the controller circuit switch closed only after it has been closed by the controller and when the switches of all floors are closed.
13. In a system of the class described, an 115 elevator car provided with a controller, a controller circuit associated therewith, a switch in the controller circuit, a gravity member cooperating with the switch and adapted to normally gravitate into a position to open the switch and render the controller ineffective to start the car, mechanical connections between the gravity member and the controller for automatically moving the gravity member into position to close the switch when the car controller is in neutral position and the car at rest, a plurality of switches corresponding to the respective floors of the building in which the elevator is installed, and electrical means controlled by said switches and cooperating with the gravity member to maintain the 120 same in a position to hold the controller circuit switch closed, when the car controller is shifted from neutral to start the car, provided that the switches of all floors are closed.
14. In a system of the class described, an 125 elevator car provided with a controller, a controller circuit associated with the controller, a switch in said circuit, mechanical connections between the switch and the controller for positively and automatically closing the controller circuit switch, a plurality of switches associated with the several floors of the building, and a maintaining circuit operable to maintain the controller circuit switch closed only after it has been closed by the controller and when the switches of all floors are closed.

- controller circuit associated with the controller, a switch in said circuit, mechanical connections between the controller and switch to automatically close said switch 5 when the controller is in neutral, a maintaining circuit for maintaining the switch closed after it has been closed by the controller, said maintaining circuit embodying a plurality of door switches associated 10 with the shaft doors, and electromagnetic means, the maintaining circuit being fed electrically so that the positive current is required to pass through all of the door switches before passing to the electromagnetic 15 means, whereby grounding of the circuit at the door switches or at any point on the positive side of the electromagnetic means will render said means ineffective to maintain the controller circuit switch closed 20 and preclude the starting of the car.
11. In a system of the class described, an elevator car provided with a controller, a controller circuit associated with the controller, a switch in said circuit, mechanical 25 connections between the controller and switch to automatically close said switch when the controller is in neutral, a maintaining circuit for maintaining the switch closed after it has been closed by the controller, 30 said maintaining circuit embodying a plurality of switches at the several floors of the building, and electromagnetic means, the maintaining circuit being fed electrically so that the positive current is required to pass 35 through all of the door switches before passing to the electromagnetic means, whereby grounding of the circuit at the door switches or at any point on the positive side of the electromagnetic means will render said 40 means ineffective to maintain the controller circuit switch closed and preclude the starting of the car, in combination with manually operable mechanical emergency means adapted to be temporarily actuated by the 45 car operator to effect the closing of the switch in the controller circuit even though the maintaining circuit is ineffective.
12. In a system of the class described, an elevator car provided with a controller, a controller circuit associated with the controller, a switch in said circuit, mechanical connections between the controller and switch for automatically closing said switch when the car controller is in neutral position and 55 the car at rest, electrical means controlled by door switches for maintaining the controller circuit switch closed when the controller is moved from neutral position to start the car, and mechanical emergency 60 means adapted to be actuated by the car operator for temporarily maintaining the controller circuit switch closed in the event that the electrical maintaining means becomes ineffective.
13. In a system of the class described, an elevator car provided with a controller, an electric circuit associated with the car, a switch in said circuit, mechanical connections between the controller and the switch for automatically effecting a closing of the switch 70 when the controller is in neutral and the car at rest, a plurality of switches positioned on the respective floors of the building in which the elevator is installed, a lock associated with the shaft door of each floor, each lock serving to control the corresponding door switch, and electrical means associated with said door switches and controlled thereby for maintaining the car circuit switch in closed condition, when the car controller is 75 moved from neutral to start the car provided that all the locks are in locked condition to close the door switches.
14. In a system of the class described, an elevator car provided with a controller, an electric circuit associated with the car, a switch in the car circuit, mechanical connections between the controller and the switch for automatically effecting the closing of the switch when the controller is in neutral 80 position and the car at rest, a lock associated with the shaft door of each floor of the building in which the elevator is installed, and electrical means controlled by all of said locks for maintaining the car circuit switch in closed condition, when the controller is 85 shifted from neutral position to start the car, provided that all of the locks are in locked condition.
15. In a system of the class described, an elevator car provided with a controller, an electric circuit associated with the car, a switch in the car circuit, mechanical connections between the controller and the switch for automatically effecting the closing of the switch when the controller is in neutral 90 position and the car at rest, a lock associated with the shaft door of each floor of the building in which the elevator is installed, and electrical means controlled by all of said locks for maintaining the car circuit switch in closed condition, when the controller is 95 shifted from neutral position to start the car, provided that all of the locks are in locked condition.
16. In a system of the class described, an elevator car provided with a controller, an electric circuit associated with the car, a switch in said circuit, mechanical connections between the controller and the switch for 100 positively effecting a closing of the switch when the controller is in neutral position and the car at rest, locks associated with the floor doors of the shaft in which the elevator is installed, and electrical means controlled by 105

said locks for maintaining the car circuit switch in closed condition when the controller is moved out of neutral position to start the car, provided that all of the door locks 5 are in locked condition.

17. In a system of the class described, an elevator car provided with a controller, an electric circuit associated with the car, a switch in the car circuit, a gravity member 10 cooperating with the switch and adapted to normally gravitate into a position to open the switch and render the controller ineffective to start the car, mechanical connections between the gravity member and the controller for moving the gravity member into position to close the switch when the car controller is in neutral position and the car at 15 rest, a plurality of door switches corresponding to the respective floors of the building 20 in which the elevator is installed and electrical means controlled by said switches and cooperating with the gravity member to maintain the same in a position to hold the car circuit switch closed, when the car controller is shifted from neutral to start the car, provided that all of the door switches 25 are closed.

18. In a system of the class described, an elevator car provided with a controller, an 30 electric circuit associated with the car, a switch in said circuit, mechanical connections between the switch and the controller for positively closing the car circuit switch, a plurality of door switches, and a maintaining 35 circuit operable to maintain the car circuit switch closed only after it has been closed by the controller and when all of the door switches are closed.

19. In a system of the class described, an 40 elevator car provided with a controller, an electric circuit associated with the car, a switch in said circuit, mechanical connections between the controller and switch to close said switch when the controller is in 45 neutral, a maintaining circuit for maintaining the switch closed after it has been closed by the controller, said maintaining circuit embodying a plurality of door switches, and electromagnetic means, the maintaining circuit being fed electrically so that the positive 50 current is required to pass through all of the door switches before passing to the electromagnetic means, whereby grounding of the circuit at the door switches or at any 55 point on the positive side of the electromagnetic means will render said means ineffective to maintain the car circuit switch closed and preclude the starting of the car.

20. In a system of the class described, an 60 elevator car provided with a controller, an electric circuit associated with the car, a switch in said circuit, mechanical connections between the controller and switch to close said switch when the controller is in 65 neutral, a maintaining circuit for maintain-

ing the switch closed after it has been closed by the controller, said maintaining circuit embodying a plurality of door switches, and electromagnetic means, the maintaining circuit being fed electrically so that the positive current is required to pass through all of the door switches before passing to the electromagnetic means, whereby grounding of the circuit at the door switches or at any 70 point on the positive side of the electromagnetic means will render said means ineffective to maintain the car circuit switch closed and preclude the starting of the car, in combination with manually operable mechanical emergency means adapted to be temporarily actuated by the car operator to effect the closing of the switch in the car circuit even though the maintaining circuit is ineffective.

21. In a system of the class described, an elevator car provided with a controller, an electric circuit associated with the car, a switch in said circuit, mechanical connections between the controller and switch to close said switch when the car controller is in neutral position and the car at rest, electrical means controlled by door switches for maintaining the car circuit switch closed when the controller is moved from neutral position to start the car, and mechanical emergency means adapted to be actuated by the car operator for temporarily maintaining the car circuit switch closed in the event that the electrical maintaining means becomes ineffective.

22. In a system of the class described, an elevator car, a controller circuit associated therewith, a controller in the car for closing this circuit at one point, a controller circuit switch for closing this circuit at another point, said switch being adapted to normally partake of open position, a plurality of door switches associated with the several floors of the building in which the elevator is installed, a door switch circuit including 105 said door switches, means included in the door switch circuit for maintaining the controller switch in closed position after it has been closed, said means being normally ineffective to close the controller circuit switch, and connections between the car controller and the controller circuit switch and adapted when the controller is in neutral to move the controller circuit switch into a position wherein it is responsive to the maintaining 110 means of the door switch circuit.

23. In a system of the class described, an elevator car, a controller circuit associated therewith, a controller in the car for closing this circuit at one point, a controller circuit switch for closing this circuit at another point, said switch being adapted to normally partake of open position, a plurality of door switches associated with the several floors of the building in which the elevator 125 130

is installed, a door switch circuit including said door switches, electro-magnetic means included in the door switch circuit for maintaining the controller switch in closed position after it has been closed, said means being normally ineffective to close the controller circuit switch, and connections between the car controller and the controller circuit switch and adapted when the controller is in neutral to move the controller circuit switch into a position wherein it is responsive to the electro-magnetic maintaining means of the door switch circuit.

24. In a system of the class described, an elevator car, a controller circuit associated therewith, a controller in the car for closing this circuit at one point, a controller circuit switch for closing this circuit at another point, said switch being adapted to normally partake of open position, a plurality of door switches associated with the several floors of the building in which the elevator is installed, a door switch circuit including said door switches, means included in the door switch circuit for maintaining the controller switch in closed position after it has been closed, said means being normally ineffective to close the controller circuit switch and mechanical connections between the car controller and the controller circuit switch and adapted when the controller is in neutral to move the controller circuit switch into a position wherein it is responsive to the maintaining means of the door switch circuit.

25. In a system of the class described an elevator car, a controller circuit associated therewith, a controller in the car and

adapted to close the controller circuit at one point, a controller circuit switch for closing the controller circuit at another point, said switch being normally maintained in open position, a door switch circuit including an electromagnet normally ineffective to close the controller circuit switch until said switch has been moved into position to render it responsive to said electromagnet, and means controlled by the controller to move the controller circuit switch into a position wherein it will be responsive to the electromagnet of the door switch circuit when the car controller is moved into neutral position.

26. In a system of the class described an elevator car, a controller circuit associated therewith, a controller in the car and adapted to close the controller circuit at one point, a controller circuit switch for closing the controller circuit at another point, said switch being normally maintained in open position, a door switch circuit including an electromagnet normally ineffective to close the controller circuit switch until said switch has been moved into position to render it responsive to said electromagnet, and mechanical connections between the controller and the controller circuit switch to automatically move the controller circuit switch into a position wherein it will be responsive to the electromagnet of the door switch circuit when the car controller is moved into neutral position.

In testimony whereof, I have signed my name to this specification.

FRANZ A. BOEDTCHER.
